Received Dec. 31st 1872

United States Patent Office.

D. F. RANDALL, OF CHICOPEE, MASSACHUSETTS.

Design No. 2,693, dated July 2, 1867.

DESIGN FOR A METALLIC BAND FOR RAILROAD CAR SEATS, &c.

The Schedule referred to in these Letters Patent and making part of the same.

TO ALL WHOM IT MAY CONCERN:

Be it known that I, D. F. RANDALL, of Chicopee, in the county of Hampden, and Commonwealth of Massachusetts, have originated and designed a New and Ornamental Metallic Band to be used upon the backs of railway car seats, and for other like purposes, of which the following is a full, clear, and exact description, reference being had to the accompanying drawings, making a part of this specification, in which—

Figure 1 is a plan view of the top of the band.

Figure 2 is a plan of the under side of the band.

Figure 3 is a vertical transverse section through line A B of fig. 1.

The top of the band *a* is made plane or flat, having the rectangular shoulders *i i* extending down a short distance to the convex surfaces *b b*, this convexity being formed by the arc of a circle of about ninety degrees, and extending from the shoulders *i i* to the lower edges of the band. The under or reverse side of the band is formed by having very minute flat or plane surfaces extending from each outer edge of the band inward, intersecting the plane surfaces *e e*, which are oblique to the plane surfaces *o o*. These oblique plane surfaces *e e* extend upward and inward until they intersect the convex surface *c* which is formed by the arc of a circle of about three degrees. This description relates particularly to its sectional contour.

This metallic band is designed to be used as a trimming to the back of a railway car seat, by being secured around its edges as a finish, and may be made of block tin or any other suitable metal.

What I claim, and desire to secure by Letters Patent, is—

The design for a metallic band for railway car seats, herein described and shown.

Witnesses:

OGDEN GRISWOLD,
M. B. RUST.
